ABSTRACT: Drapery samples of large pieces of fabric have a strip of stiffening material attached to opposite ends, and the pieces are fan folded to reduce the space required for storage. A drapery sample case provided with a rod in the upper side permits the fan-folded drapery samples to hang in the case by means of clamp hanger.

METHOD FOR PREPARING DRAPERY SAMPLES AND CASE FOR SAME

This invention relates to a method for preparing large drapery samples for carrying and displaying such samples and to the carrying container for such drapery samples.

Traditionally, interior decorators and the like carry samples of draperies, carpeting, etc. to the house, office or like where such decorators discuss decorating or redecorating of the premises with their clientele. It is, of course, preferable to show such drapery and carpeting in the setting in which it will be installed. Heretofore only small swatches of drapery fabric samples have been carried in a bundle for transportation and display. Usually the swatches of the drapery fabric are too small for accurate display of the fabric, colors and patterns, particularly when displayed against or with the carpeting and/or paint samples which may make the carpet or paint colors too dominant for effective choice of the drapery fabric.

According to the present invention, we have provided a method of preparing large drapery samples for carrying and display, which drapery samples are large enough to effectively display and show the color and pattern for the majority of fabric samples. The invention, also, provides for a carrying case for a plurality of such samples maintaining the samples in orderly fashion so that they may be easily removed from the container for displaying and returned. The method of the invention involves providing large samples of the fabric drapery, edging the samples with a stiffening edging on opposed edges, 30 fan folding the sample into a narrow, elongated rectangular sample and then heat pressing the sample so that it maintains its fan fold. The samples are hung in the fan fold for storage and transportation in the sample case. The samples may be easily spread out to their full width after displaying they are 35 easily folded back into fan fold shape.

It is therefore, an object of the invention to provide a method of preparing large, fully openable, drapery samples for carrying and displaying. Another object of the invention is to provide a method of preparing large, fully openable, drapery samples in a fan fold whereby a plurality of such samples may be suspended from an overhead support in a carrier for easy and ready access to individual samples. A further object of the invention is to provide a carrying case for a plurality of fabric samples in which a monorail track is mounted in the upper part of the sample case and a plurality of trolleys are mounted on the track for individually supporting a plurality of fabric samples suspended from the track.

These and other objects of the invention may be readily ascertained by referring to the following description and appended illustrations in which:

FIG. 1 is a side elevational view of a carrying case, according to the invention, showing the suspension of a drapery sample in said case;

FIG. 2 is an end elevational view of the case of FIG. 1;

FIG. 3 is a cross-sectional view of a portion of the case taken along section line 3-3 of FIG. 2;

FIG. 4 is an enlarged detailed view of a track and trolley for supporting drapery fabric samples in the case according to the invention;

FIG. 5 is a rear elevational view of the fabric partially prepared for fan folding;

FIG. 6 is a fan-folded sample of drapery fabric prepared according to the invention; and

FIG. 7 is a perspective view of a clamp arranged for holding drapery fabric in the carrying container.

The method of the invention provides for the use of the large, fully openable, drapery samples, and the drapery fabric is cut to provide a length H (shown in FIG. 5) which will hang in a container 20 without touching the bottom; the width of the sample determines the number of folds. The sample shown in FIG. 5 includes a body of fabric material 10 with a strip of edging material 12 secured to the top thereof and a strip of edging material 14 secured to the bottom. The edging is a pel-

lion, which is a stiff material of a loose weave, the pelon holds creases which are heat pressed into it. Thus the fabric with the attached creased pelon forms a substantially permanent pleat when formed in the strip material and the attached fabric. One very effective form of the pelon is the iron-on type, and preferably a strip of about 2½ inches wide is ironed onto the edges of the fabric layed out flat, as shown in FIG. 5. It is, also, preferable to have the length H of the fabric about 20 inches to maintain the height of the carrying case of a convenient size. The fabric may be generally about 22 inches. The fabric with the pelon edges is then fan folded, as shown in FIG. 6, to provide a series of folds 10a, 10b, 10c, etc. each of which is slightly less than 4 inches wide. This provides a fan-folded, elongated sample such as shown in FIG. 3. The fan fold effect is maintained by steam ironing the folded fabric or by otherwise pressing pleats into the edging and the fabric. The pelon edging will retain the pressed pleats and tend to return the attached fabric sample to the fan fold configuration after the sample has been displayed as a flat piece. It is important to provide the pleats in the fabric, since the samples are refolded and replaced in the case after displaying them to a prospective purchaser. The pelon edging permits the material to be unfolded and easily refolded in the same fan fold configuration a number of times.

Economically, the use of large samples instead of small swatches has proved to be beneficial to the fabric dealers. Small fabric swatches have heretofore been given to decorators, salesmen, and the like, whereas the larger samples made according to the invention may be sold to the decorators or salesmen who in turn use the samples for display or after the samples have outworn their usefulness as sales samples, they may be sold to others for their value as pieces of cloth. Thus, the fabric dealers are no longer giving away substantial quantities of fabric, and the fabric salesmen or interior decorators may recoup at least some of the cost of the sales by selling the samples as odd sizes of fabric.

The storage and carrying container of the invention is a relatively thin, rectangular case which, in one form, opens into approximately halves. The case, shown in general by numeral 20, includes one half 21 and the other half 22 which are hinged together by hinges 24 mounted at one edge of the case. Conventional luggage latches 23 provide means for maintaining the case closed when not in use. A pair of double handles 25 provide the facility for carrying the case. The use of the double handles insures that the case will remain closed while carrying even though the latches should come unlatched. The case is much like a suitcase but is divided into two halves and the two halves are substantially mirror images of each other therefore of about the same size. As shown in FIG. 3, the one half 22 is provided with a suspended monorail system, shown in general by numeral 30 which provides means for effectively hanging the samples in the case. The monorail is in effect a double I-beam with spaced clips 31 and 32 along the length of the case for suspending the I-beam from the case top. The clips fasten to the top flange 33 of the monorail system and bolts 34 and nuts 35 hold the clips to the top of the case and support the monorail system. The top flange 33 is separated from the middle flange 36 by a short web. A main web 39 separates the middle flange from a lower flange 40. A trolley arrangement includes a pair of wheels 41 and 42 secured together by means of a spring frame member 44 which holds the two wheels together on the flange 40 and permits the same to run on the lower flange. The spring frame 44 provides a loop below the monorail system for supporting drapery fabrics hooks on the monorail trolley system.

One form of a clip for holding the fabric samples on the trolley is shown in FIG. 7, and this includes a back frame member 50 having protruding teeth 52. A toothed, front frame member 51 is pivotally mounted by means of a pivot pin 55 to the back member, and a portion 57 of the back member folded under the front member provides a spring tension for holding the front member against the back member when a cover 58 is pushed toward the back member. This provides a

spring loaded clamp for clamping a fabric sample between the jaws of the clamp. A wire hook member 59 is arranged to hook over the sling frame of the trolley and suspend the sample from the monorail.

The spring frame member 44 of the trolley system provides a simple and easy means for attaching and disconnecting the trolley from the monorail. It also, provides a convenient hanger for suspending the clamp of the drapery fabric on the trolley. The trolley permits easy movement for the samples back and forth across the case for easy access to the various samples. In actual use a series of fabric samples are provided in the case and generally arranged with the various hues of each color together. This makes an arrangement which is similar to a color chart and the various shades of fabric may be quickly and easily located, then removed from the case, fully opened for comparing with colors of paint, carpeting, and the like. The samples are easily folded, the clamp replaced and returned to the case.

While the invention has been described with reference to a particular embodiment, there is no intent to limit the spirit or

the scope of the invention to precise detail so set forth except as defined in the following claims.

We claim:

1. The method for preparing large, fully openable, drapery samples for carrying in a sample case or the like and displaying and the like comprising cutting relatively large rectilinear samples of fabric, attaching a temporarily pleatable binding to opposed edges of said sample, folding said sample in a fan fold in which the folds are substantially less than the width of said sample, heat pressing said folds into the fan-folded sample so as to temporarily pleat said sample in the fan fold configuration, and attaching a removable hanger to said folded sample for storage in a carrying container and for easy opening for a full width display of said sample.

2. The method of claim 1 in which said sample is folded with folds of not more than about 4 inches.

3. The method of claim 1 wherein said folds are steam pressed into both said binding and said fabric sample.
